Robert J Mann Inventor

United States Patent Office.

ROBERT J. MANN, OF DALLAS CITY, ILLINOIS.

Design No. 4,637, dated February 7, 1871.

DESIGN FOR SIEVES.

The Schedule referred to in these Letters Patent and making part of the same.

To all whom it may concern:

Be it known that I, ROBERT J. MANN, of Dallas City, in the county of Hancock and State of Illinois, have invented a certain Design for Sieves; and I do hereby declare that the following is a full, clear, and exact description thereof, reference being had to the accompanying drawing which forms part of this specification, and which represents a central vertical section of two sieves constructed in accordance with my design, and placed one within the other.

General Description.

Sieves, as ordinarily constructed, consist of an annular band with vertical sides, which constitute the body of the sieve, with a piece of wire-netting stretched across the bottom. This band is usually made of a bent wooden strip, to which is secured the netting; but sieves have been made with this band of metal instead of wood, and having the netting swaged into the upturned bottom edge of the metal band, and it is to sieves with such metallic bands that my invention more particularly relates.

In the case of wooden bands or bodies the sieves must be made with vertical sides, owing to the difficulty of shaping the bent wood otherwise; but where the sides, or, in other words, the annular band, is

made of plate metal, any shape or configuration desired may be given thereto without difficulty; and

My invention consists in constructing the sides or annular metal band of a flaring or conical configuration, with the smallest diameter at the bottom, as is shown in the drawing.

Manufacturers of sieves find their ware to be an exceedingly bulky article to pack for transportation, as each sieve takes up the room of its entire size; but when made according to my design, with flaring sides, one sieve may be placed within another, and a pile or nest formed which will occupy a very much less space than sieves as ordinarily formed can be made to occupy, which is an item of great importance to the manufacturer and shipper.

Having thus fully set forth my design and its object and purpose,

What I claim, and desire to secure by Letters Patent, is—

The design for a metallic-band sieve, as shown and described.

ROBERT J. MANN. [L. S.]
